(57) CLAIM

The ornamental design for a night light, as shown and described.

DESCRIPTION

FIG. 1 is a perspective view of a night light showing my new design;

FIG. 2 is a front elevational view thereof;

FIG. 3 is a top plan view thereof;

FIG. 4 is a right side elevational view thereof, the left side elevational view being a mirror image thereof;

FIG. 5 is a bottom plan view thereof;

FIG. 6 is a perspective view of an alternative embodiment of a night light and base showing my new design;

FIG. 7 is a front elevational view thereof;

FIG. 8 is a top plan view thereof;

FIG. 9 is a right side elevational view thereof, the left side elevational view being a mirror image thereof; and,

FIG. 10 is a bottom plan view thereof.

The broken lines in the following drawings form no part of the claimed design.
